MINERAL OIL COMPOSITION AND IMPROVING AGENTS THEREFOR

Orland M. Reiff and Howard D. Hartough, Woodbury, N. J., assignors to Socony-Vacuum Oil Company, Incorporated, New York, N. Y., a corporation of New York

No Drawing. Original application February 3, 1940. Serial No. 317,122, now Patent No. 2,280,039, dated April 14, 1942. Divided and this application June 5, 1941, Serial No. 396,720

11 Claims. (Cl. 252—51)

This invention has to do in a general way with mineral oil compositions and is more particularly related to compositions comprised of mineral oil and a minor proportion of an added ingredient which will improve the oil in one or more important respects.

It is well known to those familiar with the art that mineral oil fractions refined for their various uses are in and of themselves usually deficient in one or more respects, so that their practical utility is limited even in the particular field for which they have been refined. For example, mineral oil fractions refined for use as lubricants have a tendency to oxidize under conditions of use with the formation of sludge or acidic oxidation products; also the lighter fractions such as gasoline and kerosene tend to oxidize with the formation of color bodies, gum, etc. In order to prevent the formation of these products and thereby extend the useful life of the oil fraction, it is common practice to blend with such oil fractions an additive ingredient which will have the effect of inhibiting oxidation, such ingredients being generally known to the trade as oxidation inhibitors or sludge inhibitors, gum inhibitors, etc.

It is also the practice to add other ingredients to mineral oil fractions for the purpose of improving "oiliness" characteristics and the wear-reducing action of such mineral oils when they are used as lubricants, particularly when the oils are used for the purpose of lubricating metal surfaces which are engaged under extremely high pressures and at high rubbing speeds.

Other ingredients have been developed for the purpose of depressing the pour point of mineral oil fractions which have been refined for use as lubricants, such refinement leaving a certain amount of wax in the oil, which, without the added ingredient, would tend to crystallize at temperatures which would render the oil impracticable for use under low temperature conditions. Additive agents have also been developed for improving the viscosity index of lubricating oil fractions. In the case of internal combustion engines, particularly those operating with high cylinder pressures, there is a decided tendency for the ordinary lubricating oil fractions to form, under such conditions of use, carbonaceous deposits which cause the piston rings to become

stuck in their slots and which fill the slots in the oil ring or rings, thus materially reducing the efficiency of the engine. Ingredients have therefore been developed which, when added to the oil, will reduce the natural tendency of the oil to form deposits which interfere with the function of the piston rings.

Aside from the corrosive action which attends the formation of acidic products of oxidation in mineral oil fractions of the lubricant range, it has been discovered that certain types of recently developed hard metal alloy bearing metals, such as cadmium-silver alloy bearings, are attacked by ingredients in certain types of oils, particularly oils of high viscosity index obtained by various methods of solvent-refining. This corrosive action on alloys of the above type has led to the development of corrosion inhibitors which may be used in solvent-refined oils to protect such bearing metals against this corrosive action.

In the lighter mineral oil fractions, such as those used for fuel purposes, particularly in internal combustion engines, it has been found that the combustion characteristics of the fuel may be controlled and improved by adding minor proportions of various improving agents thereto.

The various ingredients which have been developed for use in mineral oil fractions to improve such fractions in the various respects enumerated above are largely specific to their particular applications, and it has therefore been the practice to add a separate ingredient for each of the improvements which is to be effected.

It is a primary object of the present invention to provide a mineral oil composition which has been improved in one or more of the various properties enumerated above by the incorporation therein of a small quantity of a multifunctional compound selected from the group or class of metal-free organic compounds which is herein referred to generically as the oil-soluble or oil-miscible nuclear alkyl-substituted amino-aryl hydroxides or nuclear alkyl-substituted amino phenols in which a hydrogen of the amino group is replaced by the radical of an oxyacid which remains after removal of an acidic hydroxyl group therefrom, the said amino group being attached directly to the aryl nucleus and the term "phenols" being used in its broadest generic sense, that

is to say the term "phenols" includes both mono- and poly-cyclic hydroxyaromatic compounds. The radical of an oxyacid as just defined above is sometimes referred to herein as an "oxyacidyl" radical and the amino group ($-\text{NH}_2$) in which a hydrogen is replaced by such a radical is hereinafter referred to for convenience as an "oxyacidyl-amino" group or as an "N-esterified" group. These oil-miscible nuclear alkyl-substituted oxyacidyl-amino-aryl hydroxides should, of course, be substantially stable toward the mineral oils when intimately admixed therewith.

We have discovered that oxyacidyl-amino aryl hydroxides or oxyacidyl-amino phenols of the generic class above referred to may be added in small quantities to mineral oil fractions to form mineral oil compositions or blends superior to the unblended fractions in one or more important respects, and the present invention, therefore, is broadly directed to a mineral oil composition containing a compound falling into the general class referred to.

The oil-improving agents contemplated by this invention are all characterized by the presence of an aromatic nucleus in which at least one nuclear hydrogen has been substituted with an hydroxyl group and in which another nuclear hydrogen has been substituted with an oxyacidyl-amino radical or group. This characterizing group may be represented by the formula

in which T' represents an aromatic nucleus; (OH) represents at least one hydroxyl group and (N') represents an oxyacidyl-amino radical or group, the (OH) group and the (N') group each being attached to the nucleus (T').

The unsubstituted amino-aryl-hydroxides corresponding to the group represented by the above formula, in which the amino group contains only hydrogen and which are otherwise unsubstituted are not miscible with mineral oil, and it is therefore important that the improving agents containing the above characterizing group have additional nuclear or an amino hydrogen, or both, replaced with substituents of an oil-solubilizing nature. Preference is given to compounds of the above type in which at least one nuclear hydrogen has been replaced with an oil-solubilizing substituent since such compounds also impart or tend to impart multifunctional properties to the compound when mixed with refined petroleum distillates. By the terms "oil-miscible" or "oil-soluble" as they are used herein we have reference to that property of remaining uniformly dispersed in the mineral oil fraction either as a true solution or as a colloidal suspension during normal conditions of handling and use.

The improving agents contemplated by this invention are characterized by the presence of alkyl substituents or aliphatic radicals in the aryl nucleus, and the improving agents preferred for use in viscous mineral oils are further characterized by the presence of alkyl or aliphatic substituents in the aryl nucleus which will give other properties to the composition as a whole in addition to the oil-miscibility. We have found, for example, that where the aryl nucleus is substituted with one or more aliphatic groups corresponding to certain aliphatic hydrocarbon compounds of relatively high molecular weight (herein referred to as heavy alkyl groups), a compound or composition can be obtained which will effect marked improvement in the viscosity index

and the pour point as well as other important properties of viscous mineral oils.

As a general proposition, therefore, it may be said that the improving agents contemplated by this invention are nuclear alkyl-substituted oxyacidyl-amino-aryl hydroxides, herein termed C-alkyl oxyacidyl amino-phenols, having the characterizing group $\text{T}'(\text{OH})(\text{N}')$ described above, in which additional nuclear hydrogen is replaced with an oil-solubilizing substituent such as a predominantly aliphatic material, such substituent comprising a sufficient proportion of the composition as a whole to render the same miscible with mineral oil fractions under normal conditions of handling and use. As a further generalization it may be said that at least one point on the aromatic nucleus T' , and preferably two or more points on such nucleus, are substituted with aliphatic hydrocarbon radicals or groups, such aliphatic radicals or groups preferably being high molecular weight derivatives or heavy alkyl groups.

The simplest type of compound satisfying the above preferred requisites may be represented by the formula:

in which R represents at least one aliphatic hydrocarbon radical or group, such group or groups preferably corresponding to relatively high molecular weight aliphatic hydrocarbons and being attached to a mono- or polycyclic aromatic nucleus T and in which (OH) and (N') are as indicated above, the (N') group being preferably an oxyacidyl amino group in which the oxyacidyl group is derived from an inorganic acid, herein termed an inorganic-oxyacidyl-amino group.

As indicated above, the preferred type of compounds contemplated by the present invention are those represented by Formula I in which the group represented by R is an aliphatic hydrocarbon radical of relatively high molecular weight, preferably containing not less than 20 carbon atoms and in which the substituent represented by (N') is an inorganic oxyacidyl amino group, the latter type of compounds being hereinafter referred to as inorganic oxyacidyl-amino phenols. As also previously indicated, the compounds in which the group represented by R is a heavy aliphatic hydrocarbon radical, are preferred because of their greater oil solubility and also because such heavy aliphatic hydrocarbon radicals impart multi-functional activity to the compound or reaction product when combined with mineral oils, particularly lubricating oils.

In addition to the aliphatic or alkyl substituent R , the compounds or compositions contemplated herein as mineral oil improving agents may have additional nuclear hydrogen replaced with other substituents which may or may not have a solubilizing effect upon the composition as a whole. Such a compound in its simplest form may be represented by the formula:

in which R , T , (OH) and (N') have the same significance indicated above and in which Y represents residual hydrogen which may be replaced by a radical selected from the group consisting of: hydroxy, chlorine, alkoxy, aroxy, aralkyl, alkaryl, aryl, nitro, amino, keto, nitroso, diazo, azo, ether alcohol and ester radicals or groups. Compounds of the above general formula-type having mono-

di-, and tricyclic nuclei are illustrated by the following specific formulae:

in which (OH) and (N') have the same significance indicated above and at least one R' represents an aliphatic radical or group, preferably a heavy alkyl group, and in which the remaining R's represent residual hydrogen which may be replaced with hydroxy, chlorine, alkoxy, aroxy, aralkyl, alkaryl, aryl, nitro, amino, keto, nitroso, diazo, azo, ether alcohol and ester radicals or groups.

In the foregoing examples it will be observed that the aliphatic or alkyl substituent in the aryl nucleus is a monovalent aliphatic hydrocarbon group, but, as will appear from the hereinafter described synthesis of our preferred type of oil-improving agent, part or all of the aliphatic hydrocarbon material may be comprised of polyvalent aliphatic hydrocarbon radicals or groups in which the several valences are attached to separate aromatic nuclear groups. Compounds of this type are included under the following general formula representation:

III $R^v(T(OH)(N')Y_b)_n$

in which T, (OH) and (N') have the same significance indicated above; R^v represents at least one aliphatic or alkyl radical or group, such alkyl group or groups being attached by one valence only to at least one aromatic nucleus T, v representing the valence of the aliphatic radical R^v , which may be one to four; Y_b represents a monovalent element or group selected from the class identified above in connection with Y; b represents the number of Y's and is equal to zero or a whole number corresponding to the valences on the nucleus T not satisfied with R^v , (OH) or (N'); and n represents a whole number from one to four and indicates the total number of groups $(T(OH)(N')Y_b)$ present in the molecule represented by the formula which are attached to the aliphatic group or groups represented by R^v through the valences v .

In the foregoing general formula representation III it will be seen that the compounds represented thereby include those materials in which all of the nuclear aliphatic substituent is monovalent ($v=1$ and $n=1$) or in which all of the aliphatic substituent is polyvalent (v and n being equal to two, three, or four); or since R^v is defined as being at least one aliphatic radical or group and may therefore include several such groups, it will be seen that this general Formula III is inclusive of compounds having nuclear aliphatic groups or

radicals of different valences (from one to four) in the same molecule. Also it will be observed that since n may be any whole number from one to four, the number of aromatic nuclei T in the molecule may likewise vary from one to four. It will be seen, therefore, that the relationship between n and v in Formula III, in its broadest aspect, is such that when n is equal to one, v is equal to one; and when n is greater than one, the valence v of at least one of the R's is equal to n (in order to tie the several nuclei or T's together) the valence of any remaining R's being any whole number equal to or less than n .

As stated above, and as will appear more fully later from the description of their synthesis, these materials represented by general Formula III may contain both monovalent and polyvalent aliphatic substituents in the nucleus. Both the polyvalent aliphatic substituent and the monovalent substituent, if both are present, may be introduced in the nucleus as part of an alkylation reaction, or all or part of the monovalent aliphatic substituent may be present in the nucleus of a hydroxyaromatic starting material as low molecular weight aliphatic groups, such as methyl, ethyl, propyl groups, etc.

Compounds of the general type last described above, which include polyvalent substituted aliphatic substituents and may also include both the monovalent and the polyvalent aliphatic substituents, are included under the sub-generic formula representation.

IV $R^v(T(OH)(N')Y_bR_c)_n$

in which T, (OH) and (N') have the same significance as indicated above; R' represents at least one polyvalent aliphatic radical or group having a valence v' of two, three, or four; Y_b indicates the same group of substituents as described above for Y; R_c represents monovalent aliphatic radicals or groups; b' represents the number of Y_b 's and is equal to zero or a whole number corresponding to the valences on the nucleus T not satisfied with R^v , (OH), (N') and R_c ; c indicates the number of R_c 's and is equal to zero or a whole number corresponding to the valences on the nucleus T not satisfied with R^v , (OH), (N') and Y_b ; and n' represents a whole number from two to four and indicates the total number of the groups $(T(OH)(N')Y_bR_c)$ present in the molecule represented by the formula which are attached to the aliphatic group or groups represented by R' through the valences v' .

In the above general Formulae III and IV it will be understood that since R^v and R' are aliphatic hydrocarbon radicals of the chain type and are each attached by one valence only to each corresponding aromatic nucleus, the valence v or v' of such radical or radicals is of necessity never greater than the number n , which indicates the number of aromatic nuclei in the molecule and in Formula III is always equal to one when n equals one. Otherwise an R^v or an R' having a valence greater than the number (n or n') of aromatic nuclei would either have some of its valencies unsatisfied or else would form a condensed ring or rings by attachment at two or more points to one and the same aromatic nucleus. Such latter compounds, as already indicated from the definition of R^v or R' , are not considered as characterizing the product of the present invention although probably formed in some instances in minor amounts as unobjectionable by-products by certain of the methods of preparation herein disclosed.

A simple type of compound coming under general Formula III in which v and n is equal to one and in which there is only one oil-solubilizing aliphatic group, R^v , may be illustrated by the following formula showing T, for purposes of illustration, as a monocyclic nucleus:

A

In the above formula the chain represents the oil-solubilizing alkyl substituent (R^v), and Y_b and (OH) have the same significance as has been heretofore given to these groups.

Since group R has been defined as "at least one," it will be apparent that there may be more than one heavy alkyl substituent attached to the nucleus T, such a compound, where v and n are each one and in which there are two such monovalent R^v groups, may be represented by the following formula:

B

in which the chains and the substituent characters have the same significance defined above.

Compounds of the type satisfying the general Formula III and the sub-generic Formula IV in which R^v (or $R^{v'}$) is polyvalent and v (or v') and n (or n') are more than one and in which there is only one such polyvalent R^v group, may be illustrated by the following formula, in which the aryl nucleus T is again indicated for illustration as being monocyclic:

C

In the above formula designated by C, R_e is a monovalent alkyl group as defined above under Formula IV and is the same as monovalent R^v in Formula III.

Under this same type of compound indicated by Formula C there may also be more than one polyvalent R^v group (represented by the chain), such a compound in which there are, for example, two polyvalent R^v groups being illustrated by the following formula, in which the characterizing groups have the same significance described above under Formula C:

D

The probable molecular structure of compounds in which the aryl nucleus T is polycyclic will be obvious from the foregoing exemplary Formulae A to D inclusive, and the molecular structure of compounds in which v and n are equal to two and

four will be readily understood from the exemplary Formulae C and D.

Another possible molecular structure of compounds coming under Formula III is a compound having more than one polyvalent R^v , at least two of which have different valences. Such a compound may be typified by the following formula in which the symbols have the same significance as in Formula C:

10 E

20 As to the possible number of R^v and (R_e) groups going to make up a single molecule, this will vary with the extent to which it is desired to effect substitution of the nucleus with oil-solubilizing aliphatic groups for obtaining the desired properties in the product and is, of course, limited by the number of valences on the aromatic nucleus which are available for substitution.

As will be apparent to those skilled in the art, the maximum possible number of R^v (and R_e)

30 groups which can be attached to a single aromatic nucleus will vary as the nucleus is mono or polycyclic and also as the nucleus is otherwise substituted. It will also be apparent that available valences on the nuclei may all be attached to 35 polyvalent aliphatic substituents.

It will be understood that the oil-improving agents contemplated by this invention may be pure compounds satisfying the general Formula III described above with any one of the various 40 mono and poly cyclic aromatic nuclei as T and the various substituents (R^v (or $R^{v'}$), (N') and Y) described, the only requisites being that at least one nuclear hydrogen be substituted with an oxyacidyl-amino, another nuclear hydrogen

45 be substituted with a hydroxyl group and at least one nuclear hydrogen be substituted with an oil-solubilizing aliphatic radical or group. However, in manufacturing the preferred oil-improving product of the present invention by the preferred 50 method of procedure, as will appear more fully later on, the final oil-improving product obtained is normally or usually a mixture of different compounds corresponding to different values of n and v and to different numbers of aliphatic groups R^v .

55 As has been emphasized hereinabove, it is important that the preferred oil-improving agents as represented by general Formulae III and IV have nuclear hydrogen in the aromatic nucleus T substituted with predominantly aliphatic material which comprises a sufficient proportion of the composition as a whole, particularly when N' contains no aliphatic organic acyl radical, to render the same miscible with the mineral oil fraction in which the improving agent is used under 60 normal conditions of handling and use. It appears from the results of our research that there is a critical range in the degree of alkylation of these improving agents below which the product or agent will not satisfy the requirements for oil-miscibility.

65 Expressing this in another way, it appears that the hydroxyaromatic constituent from which the oxyacidyl-amino-aryl hydroxide is derived should not exceed a certain percentage of such alkylated hydroxyaromatic composition as a whole. This critical range of alkylation may

be roughly expressed as the ratio by weight of $(T(OH))_n$ to $R'(T(OH))_n$.

The degree of alkylation and the critical range within which operative or preferred compounds can be obtained may also be expressed as the number of carbon atoms contained in the aliphatic substituents for each aryl nucleus in a given molecule or molecular structure.

The critical range in the degree of alkylation, as defined above, of the aryl nucleus in the improving agents contemplated herein may vary with: (a) the mineral oil fraction in which the improving agent is to be used; (b) the aryl nucleus T (mono- or polycyclic); (c) the hydroxyl content of the aryl nucleus from which the oxyacidyl amino-aryl hydroxide is derived (mono- or polyhydric); (d) the character of aliphatic material comprising the substituent (straight or branched chain); (e) mono- or poly-substitution of the aryl nucleus; and (f) other substituents on the nucleus T, which may be of positive or negative or of neutral solubilizing activity.

In general it may be said that a polycyclic nucleus appears to require a higher degree of alkylation than a mono-cyclic nucleus; that a polyhydric nucleus requires a higher degree of alkylation than a monohydric nucleus; and that branched chain aliphatic substituents have a somewhat greater solubilizing action than straight chain solubilizing substituents.

In view of the foregoing variables it would be impracticable and probably misleading to attempt to give an expression and figure which would indicate accurately the proper ratio of hydroxyaromatic constituent to the alkylated hydroxyaromatic constituent which would express a degree of aliphatic substitution satisfying all cases taking these variables into account. As a guide for preparing these improving agents, however, our research indicates that for a product having pour depressing and V. I. improving properties in addition to other valuable properties the ratio, expressed as:

$$VII \quad \frac{(T(OH))_n}{R'(T(OH))_n}$$

should not be greater than 0.17 when the weight of the hydroxyaromatic nucleus or component $(T(OH))_n$ is expressed in terms of its chemically equivalent weight of phenol (C_6H_5OH). However, for mere oil-solubility with inhibition of oxidation we have found that this ratio may be raised as high as .60 or even higher by substituting the nucleus with branched chain aliphatic groups or by including an aliphatic acyl radical in the N' group. In general it may be said that in the preferred improving agents contemplated herein the ratio by weight of the hydroxyaromatic component in the product to the corresponding alkylated hydroxyaromatic nucleus or component therein should not be greater than about seventeen parts by weight of the former to about 100 parts by weight of the latter, or about seventeen per cent, when the weight of the hydroxyaromatic nucleus or component is expressed in terms of its chemically equivalent weight of phenol. It will be observed that the ratio as represented by the Formula VII above does not take into account any other substituent in the nucleus than the aliphatic substituents and the hydroxyl group; but since the aliphatic substituent is primarily relied upon in the agents contemplated herein as the solubilizing and multi-functional-producing substituent, it is believed that the foregoing expression and limits will serve

as a working guide for the preparation of oil-soluble materials and the preferred multifunctional materials.

As stated above, the degree of alkylation may also be expressed by the number of carbon atoms contained in the aliphatic substituent for a given hydroxyaromatic nucleus T. As a general guide here it may be said that the aliphatic substituents represented by R' in the above general Formula III should, for the preferred multifunctional materials contemplated herein, contain at least thirty carbon atoms for each aromatic nucleus T.

The ratio of seventeen per cent, which we may term the "phenolic ratio," represents what we consider a maximum figure for the preferred products contemplated herein, and in general it will be found that this figure will be lower, the actual ratio, of course, being dependent upon the variable factors enumerated above. For example, as will later appear, an improving agent of the preferred type in which the aliphatic substituent in the aryl nucleus is derived from petroleum wax (a predominantly straight chain aliphatic hydrocarbon of at least twenty carbon atoms) and in which the aromatic nucleus was derived from phenol otherwise unsubstituted may have a phenolic ratio, as expressed above, not substantially greater than about thirteen per cent.

A further general guide for the synthesis of the preferred improving agents for viscous oils is to alkylate the aromatic nucleus so it is poly-substituted with aliphatic hydrocarbon radicals or groups preferably of relatively high molecular weight.

As has been previously indicated, it is one of the primary objects of the invention to provide an oil-improving agent which will have multi-functional improving activity in a mineral oil. Our research indicates that compounds satisfying the requisites of general Formula III above may be blended in minor proportions with mineral oil fractions, particularly of the viscous or lubricating oil type, to effect marked improvement in several important properties. The improvement effected may be varied somewhat by varying the character of the aliphatic substituent in the aryl nucleus, petroleum wax and aliphatic hydrocarbons of similar characteristics such as ester wax, for example, giving products which effect a marked improvement in viscosity index and pour point in addition to other properties to be hereinafter pointed out. The effectiveness may also be varied with other substituents in the aryl nucleus—for example, alkoxy and especially alkyl-amino groups may contribute to solubility.

The procedure whereby the oil-improving agents contemplated herein can be prepared may be broadly described as involving the substitution of nuclear hydrogen in a nuclear-alkylated hydroxyaromatic compound with an amino (NH_2) or oxyacidyl-amino group as will be more fully explained further on.

The general procedure indicated above for preparing the oil-improving agents of the present invention has shown an alkylated or an aliphatic-substituted hydroxyaromatic compound as the starting material. Compounds of this nature, which satisfy the requirements of high alkylation for the preferred improving agents discussed above, or mixtures of such compounds can be readily prepared by alkylating a mono- or polycyclic, mono- or polyhydric, substituted or unsubstituted hydroxyaromatic compound with aliphatic compounds or predominantly aliphatic materials.

The starting material for the hydroxyaromatic constituent in the alkylation reaction to obtain an alkylated hydroxyaromatic product

in which Y_b , if present, is residual hydrogen, may be a mono- or polycyclic hydroxyaromatic compound otherwise unsubstituted; or such compounds containing alkyl substituents; or in certain special cases (to be hereinafter described) the starting material may be an alkyl-aryl ether or an aralkyl-aryl ether. For obtaining an alkylated hydroxyaromatic product containing a "Y" substituent, in addition to or in place of residual hydrogen, the starting material for the hydroxyaromatic constituent may be a mono- or polycyclic hydroxyaromatic compound in which part of the nuclear hydrogen is substituted with a member or members of the group consisting of chlorine, hydroxy, alkoxy, aroxy, aryl, alkaryl, and aralkyl groups.

Examples of the hydroxyaromatic compounds which may be used as starting material for the alkylation reaction are: phenol, resorcinol, hydroquinone, catechol, cresol, xylol, hydroxydiphenyl, benzylphenol, phenyl-ethyl-phenol, phenol resins, methyl-hydroxydiphenyl, guaiacol, alpha- and beta-naphthol, xylol naphthol, benzyl naphthol, anthranol, phenyl methyl naphthol, phenantrol, anisole, beta-naphthyl methyl ether, chlorophenol, and the like. Preference in general is to the monohydroxyphenols otherwise unsubstituted, particular preference being given to phenols and alpha- and beta-naphthol.

The alkylation of the hydroxyaromatic compound may be accomplished in various ways, such as by a Friedel-Crafts synthesis, using a halogenated aliphatic hydrocarbon, or by reaction with unsaturated high molecular weight aliphatic compounds or higher alcohols in the presence of H_2SO_4 as a catalyst.

We have found the Friedel-Crafts type of alkylation reaction to be particularly adapted to the step of preparing the alkylated hydroxyaromatic compounds from which the improving agents described herein are synthesized because it affords a convenient means of controlling the degree of alkylation and obtaining the desired "phenolic ratio" for use in the preferred mineral oil composition contemplated by this invention.

In this reaction an appropriate mono- or polychlorine-substituted aliphatic compound or material is reacted with the desired hydroxyaromatic compound in the presence of a catalytic amount of aluminum chloride. Pure or substantially pure mono- or poly- chlorine-substituted aliphatic compounds may be used. However, as will be readily understood by those skilled in the art, since it is usually very difficult to prepare or obtain high molecular weight aliphatic hydrocarbons in a pure or substantially pure state and since it is equally difficult to prepare the chlorine (or other halogen) substitution products of such hydrocarbons in a pure or substantially pure state, we prefer to employ a mixture of such hydrocarbons, such as a suitable petroleum fraction, as the starting material for our preferred improving agents, converting it into a mixture of different chlorine (or other halide) substitution products by any suitable method for use in the alkylation step. In general it may be said that the high molecular weight aliphatic hydrocarbons contemplated by this invention as preferred sources for the alkyl or aliphatic substituent R^v in Formula III above may be pure or

mixed compounds typified by those which characterize the heavier products of petroleum, such as heavy petroleum oils of the lubricant type, petrolatum and crystalline petroleum wax or other compounds or materials which will result in relatively long chain aliphatic substituents. Special preference is given to petroleum wax of melting point not substantially less than about 120° F. Such specially preferred aliphatic hydrocarbon materials commonly have molecular weights of about 250 and have at least twenty carbon atoms in their molecules.

As stated above, the Friedel-Crafts synthesis affords a convenient means of controlling the "degree of alkylation" of the product. This is accomplished by controlling: (a) the chlorination of the aliphatic hydrocarbon and (b) the reacting proportions of the chlorinated aliphatic hydrocarbon and the hydroxyaromatic compound used in the Friedel-Crafts reaction. As is well known to those skilled in the art, the replacement of nuclear hydrogen in the hydroxyaromatic compound with an aliphatic group is, in the Friedel-Crafts synthesis, effected by reaction of such nuclear hydrogen with chlorine in the chlorinated aliphatic compound, the substitution being effected with evolution of HCl . It will thus be seen that the number of chlorine substituents in a chlorinated aliphatic compound corresponds to the number of valences (v in general Formula III) which will be satisfied by or attached to hydroxyaromatic nuclei in the product of the reaction. For example, in a reaction where a quantity of pure monochloraliphatic hydrocarbon containing say three atomic proportions of chlorine is reacted with one molecular proportion of hydroxyaromatic compound, the resulting alkylated product corresponding to the constituent represented by $Rv(T(OH)Y_b)_n$ in general Formula III is one in which v and n are equal to one and there are three aliphatic groups R^v attached to one nucleus T . On the other hand, assuming a reaction in which a quantity of pure trichlor-aliphatic hydrocarbon containing three atomic proportions of chlorine is reacted with one molecular proportion of hydroxyaromatic compound, the product would be one in which v and n of general Formula III are each equal to three, and the solubilizing action of a single aliphatic group would be distributed among three nuclear hydroxyaromatic groups. It is due to this latter condition that we consider it preferable that the number of valences "v" (in R^v of Formulae III, etc.) be maintained within the range of from one to four hereinabove specified. In other words, it appears that the required oil-solubilizing and oil-improving action of the aliphatic substituent R^v , particularly where the agent is to be used for multifunctional activity in viscous oils, is not obtained with materials predominantly comprising of a compound or compounds corresponding to the constituent represented by $Rv(T(OH)Y_b)_n$ in Formula III in which v and n are greater than four. Hence, for use in the Friedel-Crafts reaction the chlorinated high molecular weight aliphatic material should be a compound, or should be predominantly comprised of compounds, in which the chlorine content is not greater than a tetrachlor compound.

As will be readily apparent to those skilled in the art, the chlorination of an aliphatic material such as a liquid petroleum fraction or a crystalline petroleum wax will normally or usually result in a mixture of mono- and poly-chloro-

phatic hydrocarbon compounds. Consequently, the product of a Friedel-Crafts reaction between such chlorinated material and a hydroxyaromatic compound will be a mixture of different compounds corresponding to different values of v and n in the formula $R^v(T(OH)Y_b)_n$ and the final oxyacidyl amino-aryl hydroxide derived therefrom will likewise be a mixture of compounds corresponding to different values of n and v in the constituent represented by $R^v(T(OH)Y_b)_n$ in general Formula III. It will be understood, therefore, that the specific values for v and n in the above formula, as well as the formula itself, relate to the different specific compounds present in such a mixture which characterize it as a product of the present invention.

However, in the case of a pure compound corresponding to general Formula III or in mixtures thereof, we have, as previously stated, discovered that for a satisfactory product, the ratio by weight of hydroxyaromatic component $(T(OH))_n$ to the corresponding alkylated hydroxyaromatic nucleus or component $(R^v(T(OH))_n$ should not be greater than a certain critical maximum ratio which varies with constituents, conditions of use, and properties desired, as discussed in detail hereinabove.

The above-mentioned ratio of hydroxyaromatic component to the corresponding alkylated hydroxyaromatic component,

$$\left(\frac{(T(OH))_n}{R^v(T(OH))_n} \right)$$

in which the hydroxyaromatic component is calculated as phenol and which is therefore herein referred to as the phenol content or "phenolic ratio," is usually calculated from the weight of the hydroxyaromatic compound used up in the alkylation reaction and from the total weight of alkylated compound resulting from such alkylation reaction, as will be readily understood by those skilled in the art.

For example, when the Friedel-Crafts synthesis is used for alkylation, the aliphatic hydrocarbon material is first chlorinated until the weight of chlorine absorbed indicates that the average composition of the chlorinated product corresponds roughly to a dichlor-aliphatic hydrocarbon. Such a product will, of course, contain some mono and tri-chlor compounds and probably some tetrachlor compounds. The reacting proportions (based on atomic proportions of chlorine to one mole of hydroxyaromatic compound) are then selected so that the theoretical product of the Friedel-Crafts reaction will give the approximate phenolic ratio desired. After the Friedel-Crafts reaction and purification of the product the weight of aliphatic material in the chlorinated aliphatic starting material is subtracted from the weight of the alkylated or aliphatic-substituted product to obtain the weight of hydroxyaromatic material $((T(OH))_n)$ actually combined or used up in the alkylation synthesis. From this value and the weight of the alkylated product

$$(R^v(T(OH))_n)$$

the phenolic ratio or phenol content can be readily calculated. If there are other substituents (Y_b) on the hydroxyaromatic nucleus in addition to the mono- or poly-valent aliphatic groups, a deduction should be made for them before calculat-

ing the phenolic ratio, an operation which will be apparent to those skilled in the art.

In the foregoing description of the Friedel-Crafts alkylation reaction we have referred to a hydroxyaromatic compound as a starting material. This same reaction may be used with an alkyl-aryl ether or an aralkyl-aryl ether which undergoes a substantial rearrangement during Friedel-Crafts alkylation to form an alkylated hydroxyaromatic compound in which the alkyl group of the ether replaces one of the nuclear hydrogen atoms.

In the event it is desired to obtain a product $R^v(T(OH)Y_b)_n$ which contains an alkoxy group as the substituent Y_b , it is preferable that the alkylation be effected with a hydroxyaromatic compound containing such alkoxy or aroxy group as a substituent and a high molecular weight unsaturated aliphatic hydrocarbon (such as polymerized isobutylene, dodecylene, tetradecylene, octadecylene, melene, etc.) or a higher alcohol (such as cetyl alcohol, myricyl alcohol, ceryl alcohol, etc.) using H_2SO_4 as a catalyst. By this procedure, the hydroxyaromatic ether can be alkylated without substantial rearrangement taking place. As an alternative procedure, polyhydric phenols can be nuclear alkylated by reaction with alcohols or unsaturates or by Friedel-Crafts reaction followed by substitution of the hydroxyl hydrogen of one hydroxyl with a low molecular weight alkyl group. In carrying out this latter procedure, alkylated polyhydric phenol is treated with an alkali alcoholate to introduce alkali metal into the OH group followed by treating with the desired alkyl halide, whereby the substitution is effected.

When it is desired to obtain a keto group as the "Y_b" in general Formula III, the alkylated hydroxyaromatic compound is reacted with an aliphatic or aromatic acid anhydride in the presence of aluminum chloride as catalyst to effect the substitution before nitrating the compound. The substitution may also be carried out by reacting the alkylated hydroxyaromatic compound with an aliphatic or aromatic acid chloride, whereby an ester group is formed, followed by rearrangement of the acyl group to the nucleus. To cause this rearrangement, sufficient $AlCl_3$ must be used as catalyst.

Nuclear Y_b substituents such as nitroso, diazo, azo, ester, alkoxy, and ether-alcohol groups are introduced after the nitration and reduction reaction by methods well-known to those skilled in the art.

A nitro group can be introduced by dinitrating the alkylated hydroxyaromatic compound, followed by selective reduction of only one nitro group, such as can be carried out by the ammonium sulfide method of reduction.

NITRATION OF ALKYLATED HYDROXYAROMATIC COMPOUNDS

The above mentioned alkylated starting material may be readily converted, into the corresponding oxyacidyl - amino - hydroxyaromatic compound, in accordance with the preferred method, by nitration, to introduce a nitro group into the nucleus, followed by reduction of the nitro group to the hydrogen of an unsubstituted amino group which may then be substituted by an oxyacidyl group corresponding to the (N') group of Formula I above. The nitration pro-

cedure may be carried out as illustrated by the following example:

EXAMPLE I
Reaction mixture

t-Amyl phenol (hydroxy-benzene) mol. 1
Benzol litre 1/3
HNO₃ {17.5% by weight H₂O
1 part HNO₃—3 parts H₂O} mols. 2

Procedure

The tert. amyl phenol is dissolved in the benzol and the nitric acid solution added slowly at room temperature at such a rate that the temperature rises to 130–140° F. and is maintained there throughout the remainder of the addition. After addition of the nitric acid is complete, this temperature is maintained for 1/2 hour. The material is then water-washed until free of acid and the benzol removed by distillation.

REDUCTION OF ALKYLATED NITROHYDROXYAROMATIC COMPOUNDS

EXAMPLE II

p-tert. Amyl nitrophenol mol. 1
Tin metal mols. 3
Conc. hydrochloric acid litres. 1.5

The amyl nitrophenol and the tin are mixed together, thereafter adding the HCl in 250 cc. portions with stirring over a period of one hour.

The reaction temperature is then raised to the boiling point and the mixture refluxed until all the tin has reacted and all the amyl nitrophenol has been reduced, which is indicated by its complete solution in the hot mixture.

The reaction mixture is then cooled, whereupon the amyl amino-phenol hydrochloride precipitated as a solid compound. The precipitate is filtered off and redissolved in one liter of water and freed of tin chlorides by passing in H₂S gas. The tin sulfides are filtered off and while still hot, concentrated hydrochloric acid is added to the reaction mixture until a permanent cloudiness appears, whereupon the material is set aside to cool. The compound obtained as the hydrochloride is a white to light yellow crystalline product.

Due to the susceptibility of alkylated amino-hydroxyaromatic compounds to oxidation in the air it has been advisable to store them in the form of the hydrochloride. Where it is desired to obtain the corresponding basic compound free, the proper amount of the hydrochloride is added to a non-aqueous solvent and neutralized with ammonia gas. A concentrated blend of the free alkylated amino-hydroxyaromatic compound can be made in mineral oil in this manner.

PREPARATION OF NUCLEAR ALKYLATED OXYACIDYL - AMINO - HYDROXYAROMATIC COMPOUNDS

When nuclear alkylated, the amino-hydroxyaromatic compounds may also be N-substituted with oxyacidyl substituents forming oil-soluble derivatives. The following methods can be used for the introduction of N-substituents.

N-ESTERIFICATION WITH OXYACIDYL GROUPS

The amino-hydroxyaromatic compounds can be esterified by treating with an acid anhydride, organic or inorganic acid chloride, with substitution of an amino (and in some instances of both amino hydroxyl) hydrogen taking place.

When an inorganic acid chloride correspond-

ing to the acid of a non-metallic or more acidic type of metalloid element such as phosphorus is used in the formation of the N-ester (or oxyacidyl) product, the reaction may be represented by the following generalized equation:

and wherein the ring nucleus represents mono or polycyclic aromatic nuclei.

Examples of acid chlorides of the inorganic acids of non-metallic or acidic metalloid elements that may be used in the N-esterification reaction mentioned above are the following: POCl₃, BC₂, SiCl₄, PCl₃, SCl₂, SeCl₂, TeCl₂, as well as the corresponding bromides and iodides.

In general, as previously indicated, any acid chloride or anhydride of an inorganic acid may be employed in the N-esterification reaction which forms an N-esterified (oxyacidyl) reaction product which is substantially stable toward mineral oils when intimately admixed therewith.

Representative examples of the organic acid anhydride or acyl halides which may be used for this purpose are the anhydrides and acyl halides of the following organic acids:

(1) Saturated aliphatic mono carboxylic acids ranging from acetic to montanic acid.

(2) Unsaturated aliphatic monocarboxylic acids such as acrylic, oleic, olaidic, crotonic, etc.

(3) Saturated aliphatic polycarboxylic acids such as succinic, oxalic, adipic, sebatic, etc.

(4) Unsaturated aliphatic polycarboxylic acids such as maleic and fumaric acids.

(5) Substituted mono and polycarboxylic aliphatic acids containing hydrogen, hydroxyl, amino, ether or keto groups such as chloroacetic acid, hydroxystearic acid, tartaric acid, glycolic acid, octyloxyacetic acid and pyroracemic acid.

(6) Aromatic monocarboxylic acids such as benzoic and naphthoic acids.

(7) Aromatic polycarboxylic acids such as phthalic acid.

(8) Alkylene-substituted aromatic monocarboxylic acids such as cinnamic acid.

(9) Aryl substituted mono and polycarboxylic aliphatic acids with carboxyl in the said chain such as phenylstearic, naphthyl stearic and naphthyl polystearic acids.

(10) Substituted aromatic mono and polycarboxylic acids containing halogen, hydroxyl, amino, alkyl, aryl, aralkyl, keto, nitro, or alkoxy in the nucleus, such as chlorobenzoic, salicylic, anthranilic, toluic, phenyl-benzoic, benzoylbenzoic, nitrobenzoic and anisic acid.

(11) Non benzenoid cyclic mono and polycarboxylic acids such as abietic and camphoric acids, and heterocyclic carboxylic acids such as furoic acid.

Of the above organic acylating agents, those corresponding to the saturated aliphatic and aromatic acids are preferred. In most cases, compounds of higher V. I. can be prepared by use of the dibasic acid chlorides because of the formation of more resinous products thereby.

Also while the present invention in its preferred form is directed primarily to the above mentioned

metal-free nuclear alkylated oxyacidyl-amino hydroxides, it is also directed to, and is considered by us to be inclusive of the closely related corresponding metal-free nuclear alkylated oxyacidyl-amino-hydroxyaromatic compounds in which the hydrogen of the hydroxy group has also been replaced with an oxyacidyl group, preferably the oxyacidyl radical of an oxy-acid of phosphorus. When such a substituted hydroxy group is also desired (which is preferred), an additional equivalent of acid halide or acid anhydride must be employed over and above that which may be required to substitute the amino group containing replaceable hydrogen, such amino groups, as is well known, being more easily substituted with an oxyacidyl than the hydroxyl group. When one mole of the nuclear alkylated amino-hydroxyaromatic compound is reacted with one mole of an inorganic acid tri-chloride (or other halide) such as POCl_3 , a chelate type compound results in which the side ring or chelate ring contains the negative element or so-called acidic metalloid in place of the metal in the corresponding well-known metal-chelate type compound, as illustrated in the reaction represented by the following exemplary equation:

Any of the other acid halides mentioned above may be substituted for the POCl_3 in the reaction represented by the above Equation c, with the formation of other similar so-called acidic metalloid chelate type compounds as will be readily understood by those skilled in the art.

It is generally believed by those skilled in the art that in the formation of any of the above chelate-type compounds the OH and amino groups must be in adjacent positions such as the ortho position.

PREPARATION OF WAX-SUBSTITUTED OXYACIDYL-AMINO-HYDROXYAROMATIC COMPOUNDS

(1) ALKYLATION OF PHENOL WITH PETROLEUM WAX

A paraffin wax melting at approximately 120° F. and predominantly comprised of compounds having at least twenty carbon atoms in their molecules is melted and heated to about 200° F., after which chlorine is bubbled therethrough until the wax has absorbed about sixteen per cent of chlorine, such product having an average composition between a monochlor wax and dichlor wax. Preferably the chlorination is continued until about one-sixth the weight of the "chlorwax" formed is chlorine. A quantity of chlorwax thus obtained, containing three atomic proportions of chlorine, is heated to a temperature varying from just above its melting point to not over 150° F., and one mole of phenol ($\text{C}_6\text{H}_5\text{OH}$) is admixed therewith. The mixture is heated to about 150° F., and a quantity of anhydrous aluminum chloride corresponding to about three per cent of the weight of chlorwax in the mixture is slowly added to the mixture with active stirring. The rate of addition of the aluminum chloride should be sufficiently slow to avoid violent foaming, and during such addition the temperature should be held at about 130° F. After the aluminum chloride has been added, the temperature of the mixture may be increased slowly over a period of from fifteen to twenty-five minutes to a tem-

perature of about 250° F. and then should be more slowly increased to about 350° F. To control the evolution of HCl gas the temperature of the mixture is preferably raised from 250° F. to 350° F. at a rate of approximately one degree per minute, the whole heating operation occupying approximately two hours from the time of adding the aluminum chloride. If the emission of HCl gas has not ceased when the final temperature is reached the mixture may be held at 350° F. for a short time to allow completion of the reaction. But, to avoid possible cracking of the wax, the mixture should not be heated appreciably above 350° F., nor should it be held at that temperature for any extended length of time.

It is important that all unreacted or non-alkylated hydroxy-aromatic material (phenol) remaining after the alkylation reaction be removed. Such removal can be effected generally by water-washing, but it is preferable to treat the water-washed product with super-heated steam, thereby insuring complete removal of the unreacted material and accomplishing the drying of the product in the same operation.

The wax-substituted phenol thus obtained may be characterized by the general formula

in which R^v represents at least one aliphatic group or radical characteristic of paraffin wax having a valence v of from one to four; T represents a monocyclic aromatic nucleus; Y_b represents residual hydrogen, b being a number corresponding to the number of valences on the nucleus T not satisfied by R^v and (OH) ; and n is a number from one to four corresponding to the valences v on the aliphatic group or groups R^v which are satisfied by the nuclear group or groups $\text{T(OH})\text{Y}_b$.

A wax-substituted phenol prepared according to the above procedure, in which a quantity of chlorwax containing three atomic proportions of chlorine (sixteen per cent chlorine in the chlorwax) is reacted with one mole of phenol, may, for brevity herein, be designated as "wax-phenol (3-16)." Parenthetical expressions of this type (A-B) will be used hereinafter in connection with the alkylated hydroxyaromatic compounds to designate (A) the number of atomic proportions of chlorine in chlor-aliphatic material reacted with one mole of hydroxyaromatic compound in the Friedel-Crafts reaction, and (B) the chlorine content of the chlor-aliphatic material. In the above example A=3 and B=16.

Wax-phenol (3-16) as obtained by the above procedure had a phenol content or a "phenolic ratio" of about thirteen per cent. Our research indicates that this phenolic ratio of thirteen per cent may be considered as representing about the maximum for satisfactory miscibility and multifunctional activity in viscous oils of the oxyacidyl-amino-aryl hydroxides in which the alkyl substituent is derived from wax and the hydroxyaromatic constituent is derived from phenol ($\text{C}_6\text{H}_5\text{OH}$).

(2) INTRODUCTION OF AMINO AND OXYACIDYL-AMINO GROUPS INTO WAX-SUBSTITUTED HYDROXYAROMATIC COMPOUNDS

(a) Introduction of amino groups

The introduction of an amino group into a wax-substituted hydroxyaromatic compound may be carried out by nitration followed by reduction in accordance with Examples I and II above (with only slight variations) which illustrate these two

steps in the conversion of tertiary amyl phenol into the corresponding tertiary amyl aminophenol. These variations consist mainly in the use of a suitable solvent or diluent for the wax-substituted compound and other minor variations such as the use of zinc dust as reducing agent which will be readily understood, by those skilled in the art, from the following example of the nitration step only of wax-substituted phenol:

EXAMPLE III—NITRATION OF WAX PHENOLS

Reaction mixture

Wax phenol (3-16, 13.7% combined phenol)	
(1 equiv.)	g 100
Stoddard solvent	cc 100
NaNO ₃ (2 equivalents)	g 25
Water	cc 60
Conc. H ₂ SO ₄	g 31

PROCEDURE

The sodium nitrate is dissolved in water and acidified with the conc. H₂SO₄, cooling to 120° F. and adding thereto the wax phenol dissolved in the Stoddard solvent. The temperature is allowed to rise to 140–160° F. during a one-hour period and then raised to 200° F. to complete the reaction. The mixture is cooled and all traces of acid removed by water-washing, thereafter removing the Stoddard solvent diluent to obtain the nitrated product.

The reduction of the nitro group of the end product of Example III above may be carried out as already stated in accordance with the reduction method of Example II with use of a solvent and other variations similar to those indicated in Example II (2) (2).

INTRODUCTION OF OXYACIDYL-AMINO GROUPS INTO NUCLEAR WAX-SUBSTITUTED AMINO-HYDROXY-AROMATIC COMPOUNDS

After introduction of an unsubstituted amino group (—NH₂) into the nuclear wax-substituted hydroxyaromatic compounds by nitration and reduction as described above the unsubstituted amino group may be N-substituted with oxyacidyl groups as previously described.

By following the above procedures several examples of wax-substituted oxyacidyl-amino phenols in which the oxyacidyl group is derived from an inorganic acid have been prepared, as follows:

Phosphorous amide of wax aminophenol (3-16).
Silicon amide of wax aminophenol (3-16).
Phosphite ester of phosphorous amide of wax amino-phenol (3-16).

In some instances where the final product is highly viscous or waxy it is sometimes desirable to use diluents in the preparation of the compounds for the purpose of reducing the viscosity of the mixtures. In the event the compounds are being prepared for incorporation in a particular oil it is convenient to employ as a diluent a quantity of the same oil with which the compounds are to be blended.

As has been previously pointed out, the alkyl substituent in these alkyl-substituted oxyacidyl-amino-aryl hydroxides should be of relatively high molecular weight. In order to obtain compounds having pour depressant and viscosity index improving properties along with other improved properties, such as sludge inhibition, etc., we have found that the alkyl substituents should preferably be in the nature of petroleum wax or an aliphatic hydrocarbon of correspondingly high molecular weight, and for that reason the wax-substituted compounds are considered pref-

erable for the purpose of this invention. Although the wax-substituted products are considered preferable for the reasons just stated, oil-miscible nuclear alkyl-substituted oxyacidyl-amino aryl hydroxides may be prepared from alkylated hydroxyaromatic compounds in which the alkyl substituent is derived from Transil oil (a highly refined viscous paraffin base white oil having a Saybolt viscosity of eighty-two seconds at 100° F. and specific gravity of 0.8498) and from tertiary amyl-phenol.

As will appear from the foregoing description, the oil-improving agents contemplated by this invention are characterized by the general formula III R²(T(OH)(N')Y_b)_n described hereinabove; such chemical compounds or products may also be characterized as oil-miscible "alkylated or alkyl-substituted oxyacidyl-amino-aryl hydroxides," it being understood that the term "alkyl" and "alkylated" are used herein in a broad sense to include polyatomic or polyvalent as well as monovalent aliphatic radicals or groups and also that the term "oxyacidyl" is inclusive of organic and inorganic oxyacidyl groups.

Also, as previously indicated, the preferred compounds are those in which a hydrogen of the amino group has been substituted with an oxyacidyl group of an inorganic acid, preferably the oxyacidyl group of an oxy acid of phosphorus and it is also a further preference that the hydrogen of the hydroxy group of the hydroxyaromatic nucleus be also substituted with such an inorganic oxyacidyl group forming a chelate type compound which is generally more stable.

While the preferred method of preparing the alkylated aminohydroxyaromatic compounds in which the amino group is unsubstituted is the nitration and reduction of the corresponding alkylated compound as described above, other methods may be employed for this purpose as follows:

(1) By reduction of alkylated nitroso-hydroxyaromatic compounds (isomeric with quinone monoximes) with the above reagents.

(2) By coupling alkylated hydroxyaromatic compounds with benzene diazonium chloride and subsequent reduction as above.

(3) By electrolytic reduction of alkylated nitro aromatic compounds.

(4) By reduction of alkylated nitro-hydroxyaromatic compounds with hydrogen in the presence of a catalyst.

For the formation of the alkylated polycyclic compounds such as amino-naphthols, procedure 2 above is the preferred method.

As will be noted, each of these methods is carried out after alkylation of the aromatic starting material. In method 3, as is well known to those skilled in the art, the aromatic nitro compound is first reduced to aryl hydroxyl amine which under the conditions undergoes molecular rearrangement into the corresponding aminohydroxyaromatic compound.

SOLUBILITY OF ALKYLATED OXYACIDYL-AMINO-PHENOLS IN MINERAL OILS

The compounds of the present invention can be rendered soluble in mineral oils when prepared from aminophenols containing C-alkyl substituents. An isoamyl substituent or a wax radical has been found necessary to give the desired solubility.

Substituents such as C-alkoxy or organic ester groups or N-alkyl, aralkyl or ester groups have solubilizing value, but are not desirable without C-alkyl substituents being present.

C-alkyl substituents are preferred to N-alkyl substituents not only for solubilizing value, but

because of the readiness of preparation and the effectiveness of oxyacidyl metalloid derivatives prepared therefrom.

To demonstrate the effectiveness of compounds or products of the type described above in the mineral oil compositions contemplated by this invention, we have conducted several comparative tests, the results of which are listed below, with representative mineral oils alone and with the same oils blended with various representative nuclear alkylated oxyacidyl-amino-aryl hydroxides.

POUR TEST

This series of tests was conducted with a mineral lubricating oil fraction having a Saybolt viscosity of 44.9 seconds at 210° F. and an A. S. T. M. pour point of +20° F. The alkyl-substituted amino-aryl hydroxides used were derived from wax-substituted phenolic compounds obtained by condensing chlorwax of substantially sixteen per cent chlorine with the phenolic compound in the ratio of one molecular proportion of phenolic compound to a quantity of chlorwax containing three atomic proportions of chlorine, this condensation product being indicated by "(3-16)" in Table I below. The aryl constituents of the compounds used in these tests were phenol. The results of these tests are listed below.

TABLE I

Action of wax-substituted oxyacidyl-amino-phenols as pour point depressants

Improving agent	0%	A. S. T. M. 1/4%	Pour test 1/4%
Silicon amide of wax-amino-phenol (3-16)	°F. +20	°F. -5	°F. -15
Phosphorous amide of the phosphite ester of wax-amino phenol (3-16)	+20	-5	-20

From the foregoing results it will be observed that the alkyl-substituted oxyacidyl amino-aryl hydroxides and esters contemplated by this invention, when present in a mineral lubricating oil in amounts as small as one-eighth of one per cent, are effective in depressing the pour point of the oil by a substantial amount. At higher percentages up to 1/4% the depression of the pour point is considerably greater, as clearly shown.

OPERATION TEST

In addition to the foregoing tests we have also made an exemplary test of an oil and an oil blend containing a representative improving agent of the type contemplated by this invention to determine the comparative behavior of the unblended oil and the improved oil composition under actual operating conditions. This test was carried out in a single cylinder CFR engine cooled with a diethylene glycol-water mixture held at a temperature of about 390° F. The engine was operated continuously over a time interval of twenty-eight hours at a speed of about 1200 R. P. M., which is equivalent to a road speed of about twenty-five miles per hour. The oil temperature was held at about 150° F. during the test.

The conditions observed at the end of the test were: (a) the extent to which the piston rings were stuck, (b) the extent to which the slots in the oil rings were filled with deposit, (c) the amount of carbonaceous deposits in the oil, and (d) the neutralization number (acidity) of the oil at the end of the test. The oil used was a lubricating oil stock of 120 seconds Saybolt Uni-

versal viscosity at 210° F. and the results, which are recorded in Table II below, show a marked improvement in mineral oil compositions of the type contemplated by this invention over the oil alone.

In running this exemplary test a comparative run was made with a sample of the blank oil for comparison with the same oil containing the addition agent. In Table II below the blank oil sample is indicated by A₅ and the oil with the addition agent used in the corresponding run is indicated by B₅. The last mentioned oil blend as set forth in Table II below contained the following addition agent in the amount indicated:

15 B₅=1 per cent silicon amide of wax-aminophenol (3-16)

TABLE II

Example of the action of an alkylated oxyacidyl-aminophenol as inhibitor in C. F. R. ring test (28 hours)

Oil	Ring condition										Grams carbon deposit	N. N.
	Degrees stuck					Percent slots filled						
	1	2	3	4	5	3	4	5				
A ₅	360	240	360	360	360	80	90	60			17.9	2.8
B ₅	0	0	0	0	0	70	70	70			14.9	0.6

The improvement produced by the improving agents of the present invention in the viscosity index of mineral oils to which they are added is clearly shown by the illustrative data in the following table:

TABLE III
Action of wax-substituted oxyacidyl-aminophenols as viscosity index improvers

Compound	Percent conc.	S. U. V. at—		V. I.
		100° F.	210° F.	
None	0	134.8	41.6	85.2
Phosphorous amide of wax-amino-phenol (3-16)	1	145.4	42.6	93.2
	2	157.0	43.8	101.6
Phosphorous amide of phosphite ester of wax-aminophenol (3-16)	1	150.4	42.6	84.6
	2	162.1	43.6	90.8
Silicon amide of wax-aminophenol (3-16)	1	143.8	42.6	94.1
	2	153.8	43.7	104.0

It will be apparent from the foregoing description that we have developed a new class of mineral oil compositions characterized by the presence in a minor proportion of an alkyl-substituted oxyacidyl-amino-aryl hydroxide as an improving agent. The improved properties obtained and the degree of improvement effected in a particular property may be varied with the various nuclear and oxyacidyl-amino (N') substituents and with the aryl constituents; also by the degree of alkylation of the aryl nucleus. As to the degree of alkylation, it is important that the aryl nucleus be sufficiently alkylated to provide a final product which is "soluble" or "miscible" in the particular mineral oil fraction with which it is to be blended; that is, one which will remain uniformly dispersed in the oil in sufficient amount to effect the desired improvement. The amount of improving agent used may be varied, depending upon the mineral oil or the mineral oil fraction with which it is blended and the properties desired in the final oil composition. The alkylated oxyacidyl-amino-aryl hydroxides described herein may be used in amounts ranging from 1/8 per cent to five per

cent, and in general compositions of the desired improved properties may be obtained with these improving agents in amounts of from $\frac{1}{6}$ per cent to two per cent.

It is to be understood that while we have described certain preferred procedures which may be followed in the preparation of the alkylated oxyacidyl-amino-aryl hydroxides used as improving agents in the mineral oil compositions contemplated by this invention and have referred to various representative constituents in these improving compounds, such procedures and examples have been used for illustrative purposes only. The invention, therefore, is not to be considered as limited by the specific examples given but includes within its scope such changes and modifications as fairly come within the spirit of the appended claims.

This application is a division of our co-pending application Serial Number 317,122 filed February 3, 1940, now Patent No. 2,280,039 patented April 14, 1942.

We claim:

1. An improved mineral oil composition comprising a mineral oil having admixed therewith a minor proportion of an oil-miscible nuclear alkylated amino-aryl hydroxide in which a hydrogen of the amino group is replaced by the radical of an oxyacid which remains after removal of an acidic hydroxyl group therefrom, the said amino group being attached directly to the aryl nucleus.

2. An improved mineral oil composition comprising a mineral oil having admixed therewith a minor proportion of an oil-miscible nuclear alkylated amino-aryl hydroxide in which a hydrogen of the amino group and the hydrogen of the hydroxyl group are replaced by the radical of an oxyacid which remains after removal of an acidic hydroxyl group therefrom, the said amino group being attached directly to the aryl nucleus.

3. An improved mineral oil composition comprising a mineral oil having admixed therewith a minor proportion of an oil-miscible nuclear alkylated amino-aryl hydroxide in which a hydrogen of the amino group is replaced by the radical of an inorganic oxyacid which remains after removal of an acidic hydroxyl group therefrom, the said amino group being attached directly to the aryl nucleus.

4. An improved mineral oil composition comprising a mineral oil having admixed therewith a minor proportion of an oil-miscible nuclear alkylated amino-aryl hydroxide in which a hydrogen of the amino group is replaced by the radical of an oxyacid of phosphorus which remains after removal of an acidic hydroxyl group therefrom, the said amino group being attached directly to the aryl nucleus.

5. An improved mineral oil composition comprising a mineral oil having admixed therewith a minor proportion of an oil-miscible nuclear alkylated amino-aryl hydroxide in which a hydrogen of the amino group is replaced by the radical of phosphoric acid which remains after removal of an acidic hydroxyl group therefrom, the said

amino group being attached directly to the aryl nucleus.

6. An improved mineral oil composition comprising a mineral oil having admixed therewith a minor proportion of an oil-miscible nuclear alkylated amino-aryl hydroxide in which a hydrogen of the amino group is replaced by the radical of an oxyacid which remains after removal of an acidic hydroxyl group therefrom, the said amino group being attached directly to the aryl nucleus and the said oxyacid being selected from the group consisting of the oxyacids of phosphorus, sulfur, boron, silicon, selenium and tellurium.

7. An improved mineral oil composition comprising a mineral oil having admixed therewith a minor proportion of an oil-miscible nuclear alkylated amino-aryl hydroxide in which a hydrogen of the amino group and the hydrogen of the hydroxyl group are replaced by the radical of an inorganic oxyacid which remains after removal of an acidic hydroxyl group therefrom, the said amino group being attached directly to the aryl nucleus.

8. An improved mineral oil composition comprising a mineral oil having admixed therewith a minor proportion of an oil-miscible nuclear alkylated amino-aryl hydroxide in which a hydrogen of the amino group and the hydrogen of the hydroxyl group are replaced by the radical of an oxyacid of phosphorus which remains after removal of an acidic hydroxyl group therefrom, the said amino group being attached directly to the aryl nucleus.

9. An improved mineral oil composition comprising a mineral oil having admixed therewith a minor proportion of an oil-miscible nuclear alkylated amino-aryl hydroxide in which a hydrogen of the amino group and the hydrogen of the hydroxyl group are replaced by the radical of phosphoric acid which remains after removal of an acidic hydroxyl group therefrom, the said amino group being attached directly to the aryl nucleus.

10. An improved mineral oil composition comprising a mineral oil having admixed therewith a minor proportion of an oil-miscible nuclear alkylated amino-aryl hydroxide in which a hydrogen of the amino group and the hydrogen of the hydroxyl group are replaced by the radical of phosphorous acid which remains after removal of an acidic hydroxyl group therefrom, the said amino group being attached directly to the aryl nucleus.

11. An improved mineral oil composition comprising a mineral oil having admixed therewith a minor proportion of an oil-miscible nuclear alkylated amino-aryl hydroxide in which a hydrogen of the amino group and the hydrogen of the hydroxyl group are replaced by the radical of silicic acid which remains after removal of an acidic hydroxyl group therefrom, the said amino group being attached directly to the aryl nucleus.
